UNITED STATES PATENT OFFICE.

ALONZO HOWARD, OF CHICAGO, ILLINOIS, ASSIGNOR OF EIGHTEEN PER CENT TO
ALBERT F. BURCHARD, OF CHICAGO, ILLINOIS.

EXPLOSIVE ENGINE.

Application filed March 3, 1923. Serial No. 622,502.

My invention relates to explosive engines and among the important objects of the invention are; to provide construction, arrangement and control which will enable the engine to start slowly and with powerful driving effort on the crank shaft; to provide construction and arrangement in which the gases are exploded when under maximum compression and at a time when the power piston is away from the dead center point and closer to the point of maximum leverage effort on the crank shaft; to provide construction and arrangement involving association of a compression cylinder structure with the power cylinder structure and interconnection between the power and compression pistons which will cause differential operation of the pistons, together with controlling means for controlling the flow of compressed gas from the compression cylinder into the power cylinder at a time when the power piston is well away from the dead center position; to provide construction and arrangement in which the compression piston stroke will overlap the stroke of the power piston and in which the compression piston will travel faster at the ends of its stroke than the power piston travels at the end of its stroke; to provide construction, arrangement and controlling means for adjusting the differential travel of the piston structures during operation of the engine so that the engine may operate through a wide range from slow powerful starting to maximum speed; to provide improved exhaust means adjustable during operation of the engine to adapt the engine for operation either on the two cycle or four cycle principle; to provide construction, arrangement and operation which will materially decrease the weight of the engine per horse power and which will enable the engine to be operated with less and lower grade fuel than has been possible heretofore; and in general to produce an engine which is more simple, more powerful, more economical and more efficient than engines of the prior art.

The above and other features of my invention are incorporated in the structure shown on the accompanying drawings.

On the drawing,

Fig. 1 is a side elevational view of the cylinder end of the engine.

Fig. 2 is a side elevational view of the connecting rod and crank end of the engine, 55

Fig. 3 is a sectional view on plane 3-3, Fig. 1,

Fig. 4 is a vertical diametral sectional view of the engine,

Fig. 5 is a sectional view on plane 5-5, 60 Fig. 4,

Fig. 6 is a sectional view on plane 6-6, Fig. 5,

Fig. 7 is a sectional view on plane 7-7, 65 Fig. 6,

Fig. 8 diagrammatically represents the relative movements of the power and compression pistons of the engine,

Fig. 9 diagrammatically represents the relative movements of the pistons for a different setting of the connecting rod connecting mechanism, 70

Fig. 10 is a side elevational view of the exhaust valve controlling mechanism,

Fig. 11 is a plan view of cam rails for the 75 exhaust valve controlling mechanism, and

Figs. 12 to 16 are diagrams for different settings and dimensions and showing the consequent relative movements between the pistons of the engine. 80

I have shown an engine structure comprising only a single cylinder unit, it being understood that my invention is equally applicable to engine structures comprising several cylinder units. 85

On the structure shown the base 1 supports the horizontally extending power cylinder *p* on which is mounted the compression cylinder *c*. Reciprocable within the power cylinder is the piston structure 2 having at its end the piston heads *lp* and *rp*. Reciprocable within the compression cylinder is the piston structure 3 having at its ends the piston heads *lc*, and *rc* respectively. The bodies of the piston structures between their heads are reduced in order to be spaced away from the cylinder walls, and the piston structures may be hollow as indicated in Fig. 3 in order to procure lightness. 95

Journaled in and extending transversely through the piston structure 2 intermediate its heads is the shaft 4 whose ends project through the longitudinally extending slots 5 and 6 (Figs. 1 and 4) in the opposite sides of the cylinder *p*, the walls of these slots forming bearing guides for the shaft ends. 100

The piston structure 3 (Fig. 3) has a similar shaft 7 extending through the bearing slots 8 and 9 formed in the opposite sides of the cylinder *c*.

At its right end the engine base 1 supports a number of bearing pedestals 10 (Figs. 2 and 4) in which is journaled the crank shaft 11 having the crank arms 12 between whose ends is the crank pin 13. Between the crank 10 shaft and the cylinder *p* the base 1 supports a pair of slide bearing frames 14 and 15 on which the blocks 16 and 17 may reciprocate horizontally. These blocks journal a shaft 18 to whose opposite ends are secured 15 the connecting rods 19 and 20, these rods extending along the opposite sides of the cylinder *p* and being secured at their inner ends to the ends of the shaft 4 of the piston structure 2. Between the blocks 16 and 17 the 20 shaft 18 receives the inner end of the crank bar 21 whose outer end connects with the crank pin 13.

Supported above the bearing frames 14 and 15 are the slide bearing frames 23 and 24 for the slide blocks 25 and 26 respectively. Journaled in said blocks is the shaft 28 engaged at its outer end by the connecting rods 29 and 30 which extend along the opposite sides of the cylinder *c* and connect at their inner ends with the ends of the shaft 7 of the piston structure 3.

Secured to and extending upwardly from the crank bar 21 at its inner end is the arm 31 which has the longitudinally extending slot 32 for receiving the block 33, this block receiving the shaft 28 between the slide blocks 25 and 26. When the crank shaft rotates the crank bar 21 will be bodily reciprocated horizontally and at the same time it will swing vertically on its shaft 18, and therefore the arm 31 will be swung laterally while it partakes of the bodily movement of the bar 21, the result being that the compression piston structure 3 will be reciprocated by the combined horizontal bodily travel and lateral swing of the arm 31 while the outer end of the crank bar 21 travels in a circle around the center of the crank shaft. The piston structure 2 of the power cylinder will, however, partake only of the bodily horizontal travel of the crank bar, the result being that the piston structures will travel at differential speeds and the compression piston structure 3 will reciprocate through a longer path than the piston structure 2 of the power cylinder. This differential speed and travel constitutes a very important feature of my invention as it enables me to obtain very useful, efficient and novel results in operation and control as will be herein-after more fully explained.

When the engine is operating the shafts 18 and 28 will reciprocate along parallel, horizontal paths. In order to adjust for any desired differential of travel and speed of

the piston structures I provide means for increasing or decreasing the radius of swing of the arm 31 effective on the shaft 28. Any suitable means may be provided. As shown I support the slide bearing frames 23 and 24 on fluid jacks 40 and 41 having the fluid supply piping 42 connected therewith. By means of suitable valve mechanism 43 the flow of fluid can be controlled to cause operation of the jacks to raise or lower the bearing frames to thus increase or decrease the distance of the shaft 28 from the shaft 18. In Figs. 1 and 2 the shafts 18 and 28 are shown in the horizontal planes of the axes of the cylinders *p* and *c* respectively, while in Fig. 4 the frames 23 and 24 are shown raised a distance to increase the swinging effect of the arm 31 on shaft 28.

At the ends of the compression cylinder *c* check valves 45 and 46 control the intake of explosive gas or mixture to the cylinder spaces *s* and *s'* between the piston heads *le* and *re* and the respective cylinder end walls, in which spaces the intaken mixture is alternately compressed as the piston structure 3 reciprocates. Explosive mixture is fed to the intake valves through a suitable manifold structure 47 into which the flow of the mixture is controlled in any well known manner as for example from a carburetor (not shown). The guide slots 8 and 9 are of such length that the spaces *s* and *s'* will never be open to such slots. The cylinder structure *c* is double acting, that is, gas is alternately taken in at the ends of the cylinder to be compressed and to be discharged into the power cylinder, the compressed gas in the space *s* being discharged into the left end *e* of the cylinder *p* and the compressed gases in the space *s'* being discharged into the right end *e'* of the cylinder *p*. The flow from the space *s* of cylinder *c* to the end *e* of the cylinder *p* is controlled by the check valves 48 and 49, while the flow from the space *s'* to the end *e'* controlled by similar check valves 48' and 49'. The construction, operation and location of these valves is clearly shown in Figs. 5, 6 and 7. The valve structure 48 comprises the valve head or disk 50 for controlling the connection of the space *s'* with the passageway 51. The valve stem 52 extends into the valve frame 53 which is seated in the wall of the cylinder *c*. Within the frame the stem has the abutment collar 54 between which and the threaded plug 55 the stem is encircled by the compression spring 56, the spring pressing the valve disk against its seat 57 to resist the flow of gas from the space *s*.

The valve structure 49 comprises the valve head or disk 58 which controls the connection between the passageway 51 and the sparking chamber 59 which communicates through port *x* with the end *e* of the power cylinder *p*. The valve disk has the stem 130

60 extending through the frame 61, and between the base of the frame and the collar 62 on the stem is the compression spring 63 which tends to pull the valve disk against its seat 64 to resist flow of gas from said passageway 51 to the sparking chamber 59. The valve structures 48' and 49' are constructed and arranged the same as the valve structures 48 and 49 and take care of the connection between the right ends of the cylinders *c* and *p*. At the opposite ends of the power cylinder *p* are the exhaust ports 65 and 65' respectively controlled by the similar exhaust valves 66 and 66'. The valve 66 has the stem 67 which is guided in the bar 68 bridging the port 65, a compression spring 69 encircling the stem between the bar and the collar 70 on the stem, the spring tending to hold the valve closed against its seat 71. The valves 66 and 66' control the outflow of exhaust gases from the outer ends of the cylinder spaces *e* and *e'*. The guide slots 5 and 6 for the shaft 4 of the piston structure *p* serve also as exhaust outlets from the inner ends of the spaces *e* and *e'*, the length of these slots being such that when the piston heads *lp* and *rp* reach the inner ends of the spaces *e* and *e'* respectively they will expose the slots for a short length of time to permit exhaust of the spent gases.

I provide means for automatically controlling the operation of the exhaust valves 66 and 66' by the movements of the piston structure 2. A bracket structure secured to the side of the cylinder *c* has the guide ends 75 and 75' for the rods 76 and 76'. The rod 76 extends to the left and receives at its end the outer end of the lever 77 which is pivoted intermediate its ends in a bracket 78 which may be on the cylinder *p*. The lower end of the lever engages with the outer end of the stem 67 of the exhaust valve 66. The rod 76' engages in a similar manner with the lever 77' which engages with the outer end of the stem 67' of the valve 66'. When the rods are shifted outwardly the respective exhaust valves will be forced inwardly against the pressure of their springs so as to permit exhaust from the outer ends of the cylinder spaces *e* and *e'*. Suspended between the inner ends of the rods is a vertical bar 79, the bar being shiftable in the sleeve bracket 80 extending from the cylinder *c* as best shown in Fig. 5. The bar at its upper end has the transverse slot 81 (Fig. 10) which receives the laterally deflected end 82 of the bell crank lever 83 which is pivoted at its elbow in the lug 84 extending from the cylinder *c*. By means of a rod 85 the lever may be rocked from a distance to raise or lower the bar 79.

At the opposite sides of the bar are the arms 86 and 86' independently suspended from their upper ends by means of a pin 87

(Figs. 3 and 10). The arm 86 intermediate its ends has the opposite lateral abutment extensions *a* and *a'* while the arm 86' has similar extensions *b* and *b'*. The rods 76 and 76' at their inner end are forked as best shown in Fig. 3, the ends *d* and *d'* of the rods being in the path of the extensions *a* and *a'* of the arm 86, while the ends *f* and *f'* are in the path of the extensions *b* and *b'* of the arm 86'. When an arm is swung in either direction its extension will engage with the respective rod to cause shift thereof and swing of the corresponding valve lever to open the corresponding exhaust valve.

When the bar 79 is down a sufficient distance the end of the arms 86 and 86' project into the path of cam rails 88 and 89 mounted on the seat 90 provided on the end of the shaft 4 of the power piston structure 2. The arm 86 extends into the path of the rail 88 while the arm 86' extends into the path of the rail 89, the rails being detachable so that rails of different lengths may be provided for the desired timing of opening or closing of the exhaust valves. In Figs. 1 and 3 I have shown the cam rails of such length that when the bar 79 is down the arms 86 and 86' will be engaged during the entire length of the strokes of the power piston so that as soon as a piston head travels towards its exhaust valve the valve will be opened and will be kept open during the entire piston stroke and will close only at the end of the stroke and will then remain closed while the respective cylinder space receives a charge of gas and the piston is returned by the explosion and expansion. When the power piston structure travels in the opposite direction after an explosion the cam rails will engage with the arms and swing them in the opposite direction to cause the other exhaust valve to open, and to be closed when the arms are released from the cam rails at the end of the stroke. By applying cam rails of different lengths and properly settling them on their support 90 the desired exhaust valve operation can be obtained. When the cam rails are of the same length and are side by side both arms 86 and 86' will be engaged during the same time to control the respective valve rods 76 and 76', but when the cam rails are longitudinally offset as shown in Fig. 11 the arms will operate independently to shift the valve rods.

The ends of the cam rails are beveled as best shown in Fig. 10 so that when the bar 79 is adjusted vertically the effective engagement of the rails with the arms can be advanced or delayed as desired. When the bar is raised to hold the ends of the arms entirely above the path of the cam rails the exhaust valves will not be operated and the engine will operate on the two cycle prin-

ciple, the only outlet for exhaust gas being then the slots 5 and 6. When the adjustment is such that the exhaust valves are operated the engine will operate on the four cycle principle.

Any suitable ignition means may be provided for igniting the explosive mixture charged into the power cylinder. Ordinary spark plugs may be placed in the ignition chambers 59 and 59' to be controlled by any suitable ignition system. I show sparking structures 95 and 95' (Figs. 1, 2 and 3) at the respective ends of the power cylinder, and as best shown in Figs. 6 and 7 the check valve disks 58 and 58' cooperate with the sparking structures to control the timing of the sparks. In each of the sparking chambers 59 and 59' there is a head 96 from which a stem 97 extends outwardly through the gland 98. A spherical enlargement or ball 99 on the stem is seated in the gland and held by the threaded plug 100, the ball forming a joint with the gland so that the stem 97 may be swung to adjust the head 96 within the sparking chamber. The ball is of some insulating material such as porcelain or asbestos composition in order to thoroughly insulate the stem and head from the engine framework. Within the head 96 is a compression spring 101 which presses against the disk 102 from which the contact pin 103 extends outwardly through the outer end of the head, the end of the pin being opposite the contact point 104 on the inner face of the corresponding check valve 58 or 58'. The stems 97 and 97' are connected by suitable conductors in the usual manner with distributor mechanism (not shown) to which the spark producing current flow is controlled by suitable timing mechanism. When the check valve 58 is forced inwardly during the discharge of compressed mixture from the compression cylinder to the power cylinder its contact point 104 will engage with the contact pin 103 and will shift the pin inwardly against the force of its spring 101, and then as the pressure in the cylinders is equalized and the check valve is released and moved back to its seat its contact point is eventually separated from the contact pin and the current flow is interrupted and an ignition spark is produced, it being understood that the engine framework and consequently the valve disks are grounded. By swinging the spark plug stems to bring the contact pins 103 closer or farther away from the respective check valves the sparking will be either retarded or advanced.

Any suitable means may be provided for setting the spark plug structures from a distance. As best shown in Fig. 3 a lever 107 is pivoted intermediate its ends on a lug 108 extending forwardly from the cylinder framework and connected at its outer end

with a rod 109 by means of which it may be swung from a distance. A link 110 connects with the lever at one side of the pivot point and extends to the stem 97 of the spark plug structure 95. A link 111 connects with the lever 107 at the other side of the pivot point and extends to the stem 97' of the spark plug structure 95'. By shifting the rod 109 the lever 107 is rocked and through the links 110 and 111 the proper setting of the spark plugs is simultaneously made. As before explained the gases compressed in the compression cylinder travel through the passageways 51 and 51' past the check valve structures 48 and 49, and through the spark chambers and ports α or α' to the respective ends of the power cylinder. The spark points are directly in the path of the gases so that they will be readily ignited.

In Fig. 8 I have represented the relative differential movements between the two piston structures for the setting of the slide frames shown in Figs. 1 and 2, and in Fig. 9 I have represented the relative differential movements for the settings shown in Fig. 4. The circle g represents the circular path of uniform travel of the crank pin 13. The horizontal movement of the shaft 18 is along the horizontal line $h-i$. The travel of the shaft 28 is along the horizontal line $l-m$. On the circle g I show 24 points spaced fifteen degrees apart and on the line $h-i$ and $l-m$ I show the points of location of the centers of the shaft 18 and 28 corresponding with the locations of the center of the crank pin 13 on the respective points on circle g . In Fig. 9 the shaft 28 travels along the horizontal line $n-o$, and on this line and also on the corresponding line $n-o$ in Fig. 4 I show the location points of the center of the shaft 28 corresponding with the locations of the crank pin 13 on the circle g . In Fig. 4 I also show in the cylinders the location points of the piston structures corresponding to the location points of the shafts 18 and 28 as the engine operates.

On the circle g I have designated by o the point which lies in the dead center line when the power piston is at the left end of the stroke, and the other points I have marked consecutively 15 to 345 in clockwise direction to designate the fifteen degrees advancements of the crank pin 13 while the engine operates. The same numbers o to 345 I also apply on the lines $h-i$ and $l-m$ to the corresponding points of location of the shafts 18 to 28.

Taking up now the operation, suppose that an explosion has just taken place in the space e' of the power cylinder and the piston structure 2 has been driven to the left end of the stroke. Let us consider first the relative movements of the piston structures, and for the setting shown in Figs. 4 and 9. At the beginning of the stroke of the power pis-

ton toward the right the crank pin 13 will be at the dead center point o of its path g and the centers of shafts 18 and 28 will be at the points o on the lines of travel $h-i$ and $n-o$. When the crank pin 13 travels to the point 15 on path g the shaft 18 and consequently the front end of the piston head $r-p$ will travel to the right to the point 15 on line $h-i$, but the shaft 28 and consequently the compression piston structure 3 will travel toward the left from the point 0 to point 15 as indicated on line $n-o$ and at the left end of the cylinder c . This is on account of the rocking or swinging movement of the arm 31 which receives the shaft 28. The piston structure 3 will now be practically at the end of its travel to the left. This movement of the piston 3 toward the left from the points 0 to 15 is comparatively rapid as the crank pin 13 is traveling practically vertically along the path g .

When the crank pin (Fig. 9) reaches the next point 30, that is after the crank pin has traveled 30 degrees along the path g the piston head $r-p$ will have arrived at the point 30 (Fig. 4) but the compression piston remains stationary as indicated on lines $n-o$. When the crank pin and power piston have reached the point 45 the compression piston 30 will have returned to the right to the point 45 which as shown on line $n-o$ is practically coincident with the zero point. In other words while the power piston has traveled toward the right from the point 0 to 45 the compression piston has traveled toward the left from the point 0 to 15 and then back to the zero point. Both piston structures then travel toward the right until the point 180 is reached which is the opposite dead center on the path g . As the power piston then travels from the point 180 toward the left to the point 195 (line $h-i$) the compression piston will continue toward the right to the point 195 indicated on line $n-o$. The compression piston will continue to the right up to the point 210 at the end of which time the power piston will have traveled to the left to the corresponding point on line $h-i$. After this both pistons travel toward the left and when the power piston has reached the point 240 the compression piston will have returned to the point 240 which appears practically coincident with the point 180 on line $n-o$. The pistons then continue to the left until they arrive together at the zero point. The stroke of the compression piston thus overlaps at both ends the stroke of the power piston and during the overlapping periods the pistons travel in opposite directions.

Referring to Fig. 9 the overlaps 0 to 15 and 180 to 210 of the compression piston are about twice the distances of the travels 0 to 15 and 180 to 210 of the power piston. The power piston travels at or close to harmonic

motion as the crank pin travels around the circular path g , the movement being slow near the ends of the stroke and reaching maximum speed at the points 90 and 270. The movement of the compression piston is the result of such harmonic movement and near the ends of the strokes the movement of the compression piston is much faster than that of the power piston.

When the pistons traveled to the left the compression piston drew in a charge of explosive mixture into the space s' , and at the end of the stroke of the power piston the spent gases in space e exhausted in greater part through the slots 5 and 6. The intaken gas in advance of the compression piston head $l-c$ is compressed during travel to the left of the pistons while the space e is fully scavenged through the exhaust valve 66, this exhaust valve having been held open by the engagement of the cam rail 88 with the arm 86 which actuated the valve rod 76. The springs 56 and 56' for the check valve structures 48 and 48' are comparatively light, but the springs 63 and 63' of the check valve structures 49 and 49' are comparatively heavy to resist opening of the valves until considerable pressure has been accumulated in the compression cylinder. The exhaust

gases forced out of the exhaust valves by the power piston will also create considerable back pressure against the check valve disks. It will also be noted in Fig. 6 that the piston heads in the power cylinder close the respective ports x or x' from the sparking chambers before the ends of the strokes are reached. As shown the ports are closed when the heads are within about 15 degrees from the ends of the strokes. In other words, referring to Figs. 4, 6 and 9, the piston head $l-p$ will have closed the port x when its front edge is at the point 345 or within 15 degrees of the o point or end of the stroke.

The exhaust valve spring pressure and the back pressure from the exhaust will hold against the pressure in the compression cylinder until after this port x has been closed. During the time that the piston head $l-p$ travels to the left from the point 345 to zero and back again to the point 15 and before reopening the port x the compression piston will have traveled from the point 345 to the zero point and beyond to the point 15 and this distance is traveled very rapidly so that there is an final heavy compression of the gas in the compression cylinder. During this travel the gas pressure will overcome the check valve spring pressure and the compressed gas will flow

through the passageway 51 into the sparking chamber 59, and then as soon as the piston head $l-p$ exposes the port x this heavily compressed gas will flow rapidly into the cylinder end e behind the piston head

125
130

- and when the pressures in the cylinders are equalized the valve disk 58 will be pulled back into closed position and its contact point 144, which during opening of the 5 valve was in engagement with the contact pin 103, will leave the contact pin to open the sparking circuit whereupon a spark will be formed and the gas ignited. During the time that the gas pressure is equalizing itself 10 and explosion results from the spark the power piston will arrive at a position where its travel is comparatively rapid. With the arrangement shown the power piston would probably arrive close to the point 45 when 15 the explosion takes place, that is, at a point well away from the dead center and where the crank is approaching maximum leverage position. The power piston is thus enabled to most advantageously respond to the 20 powerful driving explosion behind its head $l-p$, and as it travels through the 90 degrees vicinity very rapidly the exploded gases are free to expand and continue the powerful driving effort on the crank shaft. 25 The exhaust valve 66 remains closed during the entire travel of the power piston to the right and at the end of this stroke the spent gases in the cylinder space e will exhaust through the slots 5 and 6.
- 30 During travel toward the right of the piston structures the cam rail 89 will engage with the arm 86' and the rod 76' will be shifted to open the exhaust valve 66' so that the cylinder space e' will be scavenged. The 35 compression piston structure traveling toward the right will compress the gas in the space s' but the spring of the check valve 49' and the exhaust back pressure will hold the gas until after the piston head $r-p$ reaches the point 195 and has closed the port w' . At this point the compression piston head $r-c$ will be at the point 165 and then while the piston head $r-p$ travels to the right to the point 180 and back to the 40 left to the point 165 the compression piston will travel from the point 165 beyond the point 180 and to the point 210 to put the extra final pressure on the gas in the space s' . Then as soon as the piston head $r-p$ 45 reopens the port w' this heavy charge of gas will flow from the compression piston into the space e' behind the piston head $r-p$ and after the gas pressure has equalized itself and a spark has been produced in the 50 chamber 59' by the recession of the valve disk 58' the piston head $r-p$ will probably be somewhere near the point 225 when the explosion takes place, the point 225 approaching the maximum crank leverage point 55 270 so that the explosion and subsequent expansion of the gases will act against the power piston to produce powerful efficient turning effort on the crank shaft. The 60 exhaust valve 66' was closed before the explosion, that is, when the cam rail released 65

the exhaust valve controlling the mechanism, and the valve remains closed until the power piston reaches the end of its stroke to the left and then the cylinder space e will scavenge in greater part through the slots 5 and 6.

It will be noted by reference to Fig. 9 that when the power piston travels to the right to scavenge the end e' it travels throughout the greater part of the stroke, more rapidly than the compression piston. The spent gases are thus forced very rapidly through the limited outlet of the exhaust valve 66' and will therefore create considerable back pressure against the check valve 58' to assist the valve spring 63' in holding back the gas in the compression cylinder until the proper moment. This is also true when the power piston travels to the left to scavenge the end e , the compression piston lagging behind the power piston until near the end of the compression piston stroke when it accelerates to give the final powerful compression to the gas. The overlapping of the power piston strokes by the compression piston strokes and the relative rates of travel of the piston structures make it possible to retain final heavy compression of the gas just before it is charged into the power cylinder to be there exploded when the power piston is in the most advantageous starting and driving position.

In the arrangement of Figs. 1, 2 and 8 the effective radius of swing of arm 31 on the shaft 28 is less than in the arrangement shown in Figs. 4 and 9 and consequently the stroke of the compression piston is shorter. This will be apparent by comparing the distances 0 to 15 and 180 to 210 shown in Fig. 8 to those shown on Fig. 9. The arrangement of Figs. 1 and 8 will therefore produce less pressure in the compression cylinder.

In the diagram Fig. 12 the adjustment is such that the power piston and the crank pin are at about the 30 degree point when the power piston starts its forward driving effort 116 after the explosion. Fig. 13 shows the movement during the same adjustment for the return stroke of the power piston, the power piston starting its return driving stroke at about the 210 degree point after the explosion in the right end of the power cylinder.

In the arrangement of Figs. 14 and 15 the arm 31 is considerably lengthened with the result that the compression piston will travel almost to the ends of the compression cylinder to produce very heavy compression of the gas. By adjusting the automatic spark plugs (Figs. 6 and 7) or by properly controlling the ignition current flow for ordinary spark plugs the ignition of the gas may be delayed until the power piston has traveled quite a distance on its forward stroke, 45 degrees or more, and although such movement may reduce the pressure of the gases behind the pistons the excess or surplus pressure of 125 130

the gases caused in the compression cylinder will be sufficient to maintain the desired heavy pressure back of the piston at the time of the explosion. These conditions are very desirable where the engine is used on vehicles such locomotives which are utilized for hauling heavy loads, the arrangement permitting the engine to be started slowly and with powerful driving effort on the crank shaft.

In the arrangement of Fig. 16 the effective length of the arm 31 has been decreased considerably so that there will be less compression and this arrangement is suitable for high speed operation of the engine.

I thus produce a very simple double acting explosive engine which is adjustable during operation for the reception by the power cylinder of explosive mixture under the desired heavy compression and at various positions of the power piston away from the dead center point. The engine can therefore be started slowly and powerfully to exert heavy pull on heavy loads as for example when the engine is utilized in tractor trains or on locomotives, or in any other work where slow powerful starting and driving is necessary. By means of the exhaust arrangement the engine can be readily controlled during operation to operate on the four cycle principle or on the two cycle principle depending upon the service required. When the engine is used on the ordinary automotive vehicles speed changing gearing may be eliminated as the engine itself can be started slowly and powerfully and then adjusted directly for the higher speed.

Owing to the differential distance and rate of travel of the compression and power pistons comparatively tremendous pressure can be exerted on the fuel in the compression cylinder, and this will permit the use of a much lower grade of fuel as the tremendous pressure will crack up the heavier fuel to a more highly combustible fuel. The engine can also be run with less fuel per horse power as less explosive force will be necessary to drive the power piston when away from the dead center point. In other words my improved arrangement and operation enables me to obtain a certain horse power with less explosion effort behind the power piston, and as the engine frame is therefore subjected to less explosion strain it can be made much lighter so that the weight of the engine per horse power can be materially reduced.

I do not desire to be limited to the exact construction, arrangement and operation shown and referred to as changes and modifications can readily be made which will still come within the scope of the invention.

I claim as follows:

1. In an explosive engine, the combination of a power cylinder and a compression cylin-

der connected for the flow of compressed gas, a piston for said power cylinder, a piston for said compression cylinder, a crank shaft, connecting rod mechanism connecting said power piston with said crank shaft to cause rotation thereof when the power piston reciprocates, means for causing the compression piston to partake of a movement which is the resultant of the bodily movement and swinging movement of the connecting rod mechanism, and means for increasing or decreasing the effect of the swinging movement of the connecting rod mechanism on the movement of said compression piston.

2. In an explosive engine, the combination of a power cylinder, a compression cylinder, means for controlling the flow of compressed explosive mixture from the compression cylinder to the power cylinder, a piston reciprocable in the power cylinder, a piston reciprocable in the compression cylinder, a crank shaft, connecting rod mechanism connecting said power piston with said crank shaft, means controlled by the conjoint bodily and swinging movements of said connecting rod mechanism for reciprocating said compression piston, and means for adjusting the stroke of the compression piston during operation of the engine.

3. In an explosive engine, the combination of a power cylinder, a compression cylinder, means for controlling the flow of compressed explosive mixture from the compression cylinder to the power cylinder, a piston reciprocable in said power cylinder, a piston reciprocable in said compression cylinder, a crank shaft, connecting rod mechanism between said power piston and crank shaft, means controlled by the conjoint bodily and swinging movement of said connecting rod mechanism for reciprocating said compression piston, and means for adjusting the effect of the swinging movement of said connecting rod mechanism on said compression piston during operation of the engine.

4. In an explosive engine, the combination of a power cylinder, a compression cylinder, means for controlling the flow of compressed explosive mixture from the compression cylinder to the power cylinder, a piston for the power cylinder, a piston for the compression cylinder, a shaft, a connection between said power piston and shaft for rotating said shaft when said power piston reciprocates, means controlled by the movement of said connecting mechanism for reciprocating said compression piston, and means for adjusting the stroke of said compression piston during operation of the engine.

5. In an explosive engine, the combination of a power cylinder, a compression cylinder, means for controlling the flow of compressed gas from the compression cylinder to the power cylinder, a piston for the power cyl-

inder, a piston for the compression cylinder, a crank shaft, connecting rod mechanism between said power piston and said crank shaft for rotating said shaft when the power piston reciprocates, means controlled by the resultant bodily and swinging movement of said connecting rod mechanism to cause said compression piston to be reciprocated the same number of strokes per unit of time as said power piston but with its strokes longer than those of the power piston, and means for adjusting the effect of the swinging movements of the connecting rod mechanism on said compression piston during operation of the engine.

6. In an explosive engine, the combination of a power cylinder, a compression cylinder, means for controlling the flow of compressed gas from the compression cylinder to the power cylinder, a piston for the power cylinder, a piston for the compression cylinder, slide block mechanism, connecting rods connecting said power piston with said slide mechanism, a crank shaft, a crank bar pivoted in said slide bar mechanism and connected with said crank shaft to be bodily shifted and swung to rotate the drive shaft when the power piston reciprocates, an arm on said crank bar, and connecting rods connecting said compression piston directly with said arm whereby said compression piston will be reciprocated by a resultant of the bodily and swinging movements of said crank bar.

7. In an explosive engine, the combination of a power cylinder, a compression cylinder, means for controlling the flow of compressed gas from the compression cylinder to the power cylinder, a piston for the power cylinder, a piston for the compression cylinder, slide block mechanism, connecting rods connecting said power piston with said slide block mechanism, a crank shaft, a crank bar pivoted in said slide bar mechanism and connected with said crank shaft to be bodily shifted and swung to rotate the drive shaft when the power piston reciprocates, an arm on said crank bar, and means for adjusting the connection of said compression piston connecting rods with said arm whereby to adjust the length of the stroke of said compression piston.

8. In an explosive engine, the combination of a power cylinder, a compression cylinder, means for controlling the flow of compressed gas from the compression cylinder to the power cylinder, a piston for the power cylinder, a piston for the compression cylinder, a crank-shaft, an L shape crank-bar, connecting rods connecting said power piston with said crank-bar at its elbow, one end of said crank-bar being connected with said crank-shaft, and connecting rods connecting said compression piston with the other end of said crank-bar whereby said

compression piston will partake of the combined bodily and swinging movements of said crank-bar.

9. In an explosive engine, the combination of a power cylinder, a compression cylinder, means for controlling the flow of compressed gas from the compression cylinder to the power cylinder, a piston for the power cylinder, a piston for the compression cylinder, a crank-shaft, an L shape crank-bar, connecting rods connecting said power pistons with said crank-bar, at its elbow, one end of said crank-bar being connected with said crank-shaft, and connecting rods connecting said compression piston with the other end of said crank-bar whereby said compression piston will partake of the combined bodily and swinging movements of said crank-bar when the engine is running, and means for adjusting the connection of said compression piston connecting rods with said crank-bar for changing the stroke of said compression piston.

10. In an explosive engine, the combination of a power cylinder, a compression cylinder, means for controlling the flow of compressed gas from the compression cylinder to the power cylinder, a piston for the power cylinder, a piston for the compression cylinder, a crank-shaft, an L shape crank-bar, connecting rods connecting said power piston with said crank-bar at its elbow, one end of said crank-bar being connected with said crank-shaft, and connecting rods connecting said compression piston with the other end of said crank-bar whereby said compression piston will partake of the combined bodily and swinging movement of said crank-bar when the engine is running, and means controllable during running of the engine for adjusting the effect of the swinging movement of said crank-bar on said compression piston whereby the stroke of said piston may be regulated.

11. In an explosive engine, the combination of a power cylinder, a compression cylinder, means for controlling the flow of compressed gas from the compression cylinder to the power cylinder, a piston for the power cylinder, a piston for the compression cylinder, a crank-shaft, a crank-bar connected at one end with said crank-shaft, connecting rods connecting other end of said crank-bar with said power piston, an arm extending from said crank-bar, a connecting rod extending from said compression piston and having connection at their outer end with said arm whereby said compression piston will partake of the combined bodily and swinging movements of said crank-bar, and means controllable during running of the engine for shifting said connection toward or away from said crank-bar whereby the swinging movement effect and consequently the stroke of said compression

piston may be regulated during running of the engine.

12. In an explosive engine, the combination of a power cylinder, a compression cylinder, a piston for said power cylinder, a piston for said compression cylinder, a crank-shaft, a transmission train connecting said power piston with said crank-shaft to translate the movement of said power piston into rotary motion of said crank-shaft, a connection between said compression piston and said train for causing travel of said compression piston when said power piston is operated, and means for adjusting said connection during running of the engine to thereby control the stroke of said compression piston independently of said power piston movement.

13. In an explosive engine, the combination of a power cylinder, a piston therefor, a compression cylinder and a piston therefor, a crank shaft, connecting mechanism between said crank shaft and said pistons, and means operable during running of the engine for causing prolongation or shortening of the compression cylinder piston stroke at both ends thereof.

14. In an internal combustion engine, the combination of a power cylinder and a piston therefor, a compression cylinder and a piston therefor, a crank shaft, connecting mechanism between said shaft and said pistons for causing the compression piston

travel to overlap the travel of the power piston at both ends of the stroke, and means 35 operable during running of the engine for varying said overlap.

15. In an internal combustion engine, the combination of a power cylinder and a piston therefor, a compression cylinder and a 40 piston therefor, a crank shaft, connection between said shaft and said pistons for causing movement of said pistons in the same direction during the major portion of their travel and for causing them to travel in opposite directions at both ends of their reciprocations, and means operable during running of the engine for varying the extent of such opposite movements.

16. In an internal combustion engine, the 50 combination of a power cylinder and a piston therefor, a compression cylinder and a piston therefor, a crank shaft, unyielding connection between said shaft and said pistons, means causing the compression piston 55 to travel rapidly and powerfully at the ends of its strokes in a direction opposite to that of the power piston while the power piston is leaving its dead center position, and means operable during running of the engine for 60 varying the stroke of said compression piston.

In witness whereof, I hereunto subscribe my name this 27th day of February A. D., 1923.

ALONZO HOWARD.
